TACK DETECTING DEVICE

Charles G. Hilton, Amarillo, Tex.

Application August 12, 1943, Serial No. 498,348

4 Claims. (Cl. 177—311)

This invention relates to an improvement in tack detecting device, especially for use on the inside of boots or shoes.

In the manufacture of shoes, tacks are employed as temporary fastenings for holding the soles or insoles to the last and for holding the uppers temporarily in lasted positions. Such tacks are driven through the upper or sole, and although it is intended that the manufacturer of shoes should remove the tacks therefrom, some of these tacks are frequently overlooked and remain in the shoe until it is ready for sale to the ultimate consumer and for use.

The only way used commercially of detecting such tacks is to run the hand into the shoe and feel about on the inside, or if this is not done, the tack would not be detected until the foot is thrust into the shoe. In either event a stray tack left in the shoe often results in injury to the hand or foot before it can be detected and withdrawn.

The object of this invention is to provide for the detection of such tacks in shoes by mechanical means which will indicate the presence of the tack and the necessity for removing it, without danger of injury to the person in this operation.

This object is accomplished by the provision of a head so constructed as to be thrust into the shoe or boot and carrying thereon a feeler which may be moved about within the shoe. If a tack is encountered by the feeler, provision is made for the operation of an annunciator in response to such contact, to indicate to the inspector the necessity for thus withdrawing the tack from the shoe. This detection device includes preferably a switch connected with the feeler and so constructed as to be operated in response to movement of the feeler in any direction by engagement with the tack, for closing an electric circuit to the annunciator to energize the latter and thereby indicate the presence of the tack.

The invention includes also a feeler and contact structure of improved characteristics, simple in design, inexpensive to manufacture, and a material improvement in the manner in which it is operated to close an electric circuit in response to certain movement of the feeler in any direction. The feeler is mounted loosely on a head that is capable of manual manipulation for freedom of movement in any direction relative thereto.

A preferred embodiment of the invention is illustrated in the accompanying drawing in which:

Fig. 1 is a side elevation of the detecting device;

Fig. 2 is a longitudinal sectional view therethrough;

5 Fig. 3 is a bottom plan view thereof with the bottom cover removed;

Fig. 4 is a cross section through the body of the tool on the line 4—4 of Fig. 1;

10 Fig. 5 is a similar view on the line 5—5 of Fig. 1;

Fig. 6 is a diagrammatic view of the wiring circuit of the signal device; and

Fig. 7 is a side elevation of the tool shown applied and in use in a shoe.

15 The tool shown as an embodiment of this invention is constructed of a head 1 which is preferably formed of electrical insulating material, such as molded plastic, porcelain, rubber or the like. This head 1 is shaped somewhat triangular in plan, as shown in Fig. 3, and tapers downward from the back end to the forward end thereof, as shown in Figs. 1 and 2. This configuration adapts it readily for insertion into the toe portion of a shoe, as is evident from Fig. 7.

20 The upper back end portion of the head 1 is provided with concave grooves 2 to provide a handhold therebetween to permit grasping of the head by the hand of the operator for guiding it into and about in the shoe.

25 The head 1 has a recess 3 formed in the rear portion thereof adapted to enclose circuit closing means as hereinafter described. The recess 3 is enclosed at the bottom by a cover plate 4 detachably secured in place as by screws 5, to the lower edges of the body 1 at the rear thereof. The body 1 is cut away at the bottom of the forward end portion thereof to form a bottom face 6 spaced above the lower edges of the body 1 at the rear thereof, as will be evident from Figs. 1 and 2. This leaves an opening between the bottom cover 4 at the back portion of the head 1 and the bottom face 6 at the forward portion of said head.

30 A feeler 7 extends into said opening, as shown in Figs. 2 and 3, and projects outwardly therefrom and about the edges of the forward portion of the head 1, both laterally and forwardly of said edges. This feeler is made preferably of wire square in cross section, and is shown as

35 having an annular configuration. The disposition thereof spaced slightly outwardly from lateral confines of the forward end portion of the head 1, as well as below the lower face of this portion of the head, so disposes the feeler 55 that it will be in close proximity to the bottom

surface of the shoe in position to contact any projecting tacks therein. The feeler is held slightly above the bottom surface by a guide 8 projecting downwardly through the feeler from the head 1. This guide is shown and preferably formed of an adjusting screw threaded through the head and provided with a rounded lower end in position to bear upon the bottom surface of the shoe.

The feeler 7 is secured to a guide stem 9 at one end of the latter, which stem extends slidably through a slot 10 (Fig. 5) in a bracket 11 rigidly mounted in the recess 3 of the head with a depending portion forming a guide for the stem 9. The stem 9 is held normally in a central position with respect to the bracket by springs 12 and 13 coiled around the stem, thus retaining not only the stem but also the feeler 7 in their normal positions, as shown in Fig. 3. The rear end portion of the feeler 7 is guided also by its bearing relation upon the upper surface of the bottom cover 4, as shown in Fig. 2.

The rear end of the stem 9 has a contact plate 14 fixed thereon, and disposed within embracing opposite sides of a substantially U-shaped contact 15 in position for engaging the contact 15 and closing a circuit therat in response to bodily movement of the contact plate 14 either axially or transversely of the stem 9, as said stem is moved in response to engagement of the feeler 7.

An electric cable 16 is connected with the rear end portion of the head 3 through which cable extend electric wires 17 and 18 which are connected respectively with the bracket 11 and contact member 15, which elements are constructed of electrically conducting material. The bracket 11 is electrically connected through the coil spring 12 with the contact plate 14.

The parts 14-15 thus form an electric switch within the head, adapted to close an electric circuit between the wires 17 and 18 whenever the stem 9 is moved appreciably in response to movements of the feeler 7 either longitudinally or transversely of the head 1, sufficiently to engage the contact plate 14 with the contact member 15 at any points of the latter. The wires 17, 18 are adapted to be connected in circuit with an annunciator or signal device, such as an electric lamp shown at 19 in Fig. 6, which will be accomplished upon closing of the circuit at 14-15, thus indicating to the inspector the engagement of the feeler 7 with a tack in the shoe, and the necessity for withdrawing such tack before the shoe is used.

It will be noted that the shape and size of the head 1 is such that the head may be inserted into a shoe and moved about therein, either longitudinally or transversely. Engagement of the feeler 7 with a tack during either of such movements will be sufficient to close the electric circuit at 14-15 because the feeler is free to move in any direct relation to the head and the contact device responds to any such movements. Even if the tack should engage the feeler on the inside of the loop forming the latter and tend to move it outwardly, this would still be sufficient to close the circuit to the indicator. The stem 9 is free to

move longitudinally as well as transversely in response to these movements of the feeler, thus to engage some part of the contact plate 14 with an adjacent portion of the contact member 15.

5 While the tack detection tool is intended primarily for contacting and indicating the presence of tacks in boots and shoes, it is evident that it may be used in other articles or industries, wherever a feeler of this character may be found desirable.

10 I claim:

1. In apparatus for use in detecting a tack in a shoe, the combination of a head of a size and shape adapted to be inserted in a shoe and to be moved about the sole portion thereof, a feeler member carried by the head for movement relative thereto, said feeler member extending in a circumferential direction about the toe portion of the head in spaced relation with the peripheral confines thereof, and annunciator means operatively connected with the feeler member for annunciating action in response to movement of the feeler member relative to the head upon engagement with a tack in the shoe.

2. In apparatus for use in detecting a tack in a shoe, the combination of a head of a size and shape adapted to be inserted in a shoe and to be moved about the sole portion thereof, a feeler member carried by the head for movement relative thereto, said feeler member being constructed to extend about the front end portion of the head in spaced relation therewith, means mounting said feeler member on the head for freedom of movement in all directions relative thereto, an annunciator means operatively connected with the feeler member for yielding action in response to bodily movement of the feeler member upon engagement with a tack in the shoe.

3. In apparatus for use in detecting a tack in a shoe, the combination of a head of a size and shape adapted to be inserted in a shoe and to be moved about the sole portion thereof, a feeler member including a loop extending about the front end portion of the head in spaced relation therewith, means mounting the loop on the head for freedom of movement in all directions relative thereto, and circuit closing means carried by the head actuated in response to movement of the feeler member by engagement with a tack in the shoe and adapted to close an electric circuit to annunciator means.

4. In apparatus for use in detecting a tack in a shoe, the combination of a head of a size and shape adapted to be inserted in a shoe and to be moved about a sole portion thereof, a feeler member, means mounting said feeler member on the head for movement relative thereto, said feeler member being movable transversely relative to the head upon engagement with a tack in the shoe, and circuit closing means carried by the head and operatively connected with the feeler member for actuation in response to movement of the feeler member by engagement with a tack in the shoe for closing an electric circuit to annunciator means.

CHARLES G. HILTON.
